ATTYS.

UNITED STATES PATENT OFFICE

WILLIAM C. COLLIGNON, OF CHICAGO, ILLINOIS

FOLDABLE TABLE

Application filed May 4, 1931. Serial No. 534,788.

This invention relates to folding articles of furniture of the portable class, and particularly to folding tables, benches, stools and other articles having legs and a flat upper surface, being primarily concerned with the mechanism for enabling the articles to be folded into compact form for easy transportation and so as to occupy a small space.

In the past, devices of this type have in general embraced a flat surface, as for example, the top of a table, which may be of single or unitary construction in small sizes and foldable sections in the larger sizes. Regardless of size, these articles have in the main, included folding legs or supports at the ends of the tables. While this construction served quite adequately for articles of relatively small size, the prior art construction was objectionable when used in the larger size articles, since there would be a tendency for the table top to sag, when loaded, especially was this true in tables having very long tops. Obviously, this construction is disadvantageous in that it is often very important that the top should remain perfectly flat when the table is loaded.

This invention has, therefore, been designed to overcome the above noted defects and objections, in the provision of a foldable table which is adapted to be folded to assume an exceedingly compact form, and yet of such construction, that it may be embodied in relatively large tables with equal facility.

It is a further object of this invention to provide an intermediate foldable support for the table, which is adapted to automatically assume its extended position when the table is unfolded, and which will in the unfolded position, retain the support rigidly against movement.

It is also an object of this invention to provide anti-friction means, particularly in foldable tables which are too heavy to be easily carried, whereby the table may be easily and readily moved from one location to another, when in the folded position.

Some of the more salient features, characteristics and advantages of the device embodying the present invention have been

above set forth, others will become apparent from the following disclosures.

The invention includes these and other features of construction and combination of parts, hereinafter described and shown in a preferred form in the drawing, as more particularly indicated by the claims.

On the drawing:

Figure 1 is a view in elevation of a device embodying principles of my invention, shown adjusted to position for use as a table or the like.

Figure 2 is a bottom plan view of the device, showing the end supporting members in folded position.

Figure 3 is a side elevation of the device in folded position.

Figure 4 is a vertical transverse section taken substantially on line IV—IV of Figure 1.

Figure 5 is an enlarged fragmentary view, showing the manner in which the intermediate support and top sections are connected together, and also the relative positions of the supporting members and top sections when folded.

Figure 6 is an enlarged fragmentary elevational view of a portion of the bracing means for the end supporting members.

As shown on the drawing:

In the illustrated embodiment of this invention there is shown a foldable table, but it is to be noted that many and other varied uses or devices may be adapted or formed embodying features of the present invention, as will become apparent to one skilled in the art, without departing from the spirit and scope of the invention. For example, the invention may be incorporated in seats, benches, and the like.

The table as shown in the present embodiment comprises a pair of top sections 1 and 2, as shown in Figure 1, which are arranged in end to end alignment with the adjacent ends abutting. These top sections are respectively hingedly connected by means of hinges 3 and 4 to the upper margin of a supporting member 5 so that when the table is in unfolded position, the joint 6 between the abutting ends of the top sections is cen-

trally disposed of the top edge of the support 5, the ends of the sections bearing against and being supported by the member 5, thereby rigidly retaining the supporting member 5 against displacement when the table is unfolded and set up in a position for use. These hinges also enable relative pivotal movement between the top sections 1 and 2 and the supporting member 5 so that when the table is folded, these sections and supporting member will be in spaced juxtaposed relationship as indicated by the dotted lines in Figure 5. It is to be noted that in the folded position, the top sections are disposed outwardly from the supporting member 5, and that the previously abutting ends, that is, the hinged ends of the sections project beyond the hinged end of the supporting member 5, thereby serving to seal and protect the hinged members against damage when the table is being moved from one location to another.

Since the under structures of the sections 1 and 2 are identical, except for their opposite dispositions, only one set need herein be described. A pair of spaced legs 7-7 joined at their upper ends by a strip or yoke 8 are hinged on the under side of each of the sections 1 and 2 as indicated at 9. In order to increase the stability and provide adequate rigidity, the legs 7-7 are connected adjacent their free ends by a bracing member 10. It is to be noted that when the table is set up and the legs 7-7 are in upright position, the upper edge of the yoke 8 abuts the under surface of the section to which it is connected thereby providing additional rigidity which tends to prevent the table from wobbling.

In order to prevent folding the legs 7-7 and rigidly retain them in upright position when the table is set up, bracing means are provided which connect between the legs and the top section with which the legs are associated. These means comprise a pair of upwardly converging members 11-11 which are pivotally connected at their lower ends as indicated at 12 to the inner surfaces of the legs. The adjacent ends of the members 11 are deflected to form spaced parallel lugs 13-13 which are provided with aligned apertures for receiving a pivot pin 14. This pivot pin forms a pivotal connection to a bracing member 15 having one end disposed between the lugs 13-13 and its other end pivotally connected to a suitable bracket 16 secured to the under side of the section to which the legs are connected.

With the foregoing arrangement, it will be observed that when the legs 7-7 are in upright position, the bracing members 11-11 and 13 are extended and lie in the same plane, as shown in Figure 1. When, however, the legs 7-7 are folded against the under side of the section to which they are connected, the bracing members are folded

so that the bracket 16 is disposed between the pivotal connections 12 of the members 11 to the legs, and the bracing members lie within the same plane. In order, however, to securely retain the bracing members in extended aligned position, when the table is set up, I prefer to provide suitable clamping means, whereby the members 11 and 13 may be secured against relative pivotal movement. For this purpose, the upper edges of the lugs 13-13 are provided with aligned recessed portions 17 for receiving a clamping screw 18 which extends through and threadedly engages the end of member 15. One end of this screw is provided with a wing head 19 which may be tightened against the surface of the lug 13 adjacent one of the recessed portions to securely clamp the members 11 and 15 in extended position.

In large size tables, I have found it particularly advantageous to provide anti-friction means, whereby the table may be conveniently rolled without the necessity of having to lift the entire table, from one position to another. The anti-friction means comprises ball retaining sockets 20 which are mounted in the free ends of the top sections 1 and 2 and have rotatably mounted balls 21 therein which project past the edges of the top sections, as best shown in Figure 5. As shown in Figure 3, it will be noted that when the table is folded, the balls 21 in each top section are spaced apart and enable the folded table to be supported upon the balls and slidably move from one location to another.

From the foregoing, it will be apparent that I have provided a foldable table or similar device which is readily and easily folded to assume an exceedingly compact form, and yet of such construction that it may be embodied in relatively large tables; a table which is provided with an intermediate foldable support arranged to automatically assume an extended position when the table is unfolded and set up for use, this support being rigidly held against movement, when the table is in position of use; and which is provided with novel anti-friction means whereby the folded table may be easily and readily moved from one location to another, without the necessity of having to lift the entire weight of the table.

Now, it is of course to be understood that although I have described in detail the preferred embodiment of my invention, the invention is not to be thus limited but only insofar as defined by the scope and spirit of the appended claims.

I claim as my invention:

1. A folding table comprising a pair of top sections in end to end relationship with their inner ends abutting, a support common to the abutting ends of said sections,

the upper edge of said support being of such width as to extend over the under surface of the abutting ends of said sections, and hinge means connecting each side of the support to the end of the section contiguous thereto, said means being arranged to enable folding of said sections and support into superposed relationship.

2. A folding table comprising a pair of top sections in end to end relationship, a common support for the contiguous ends of said sections, hinges on the opposite sides connected to the respective sections, said hinges being disposed in such a manner as to enable the under surfaces of the contiguous ends to engage against the upper edge of the support, when the sections are in the same plane, whereby the support is rigidly held against movement relative to said sections, and other supports for the outer ends of said sections.

In testimony whereof I have hereunto subscribed my name at Chicago, Cook County, Illinois.
